ASH DISCHARGE LOCK CHAMBER FOR
GAS GENERATORS

Arthur Graham Glasgow, London, England, assignor to United Engineers & Constructors Inc., Philadelphia, Pa., a corporation of Delaware

Application April 25, 1930, Serial No. 447,141
In Great Britain May 4, 1929

4 Claims. (Cl. 48—78)

In generators or producers for the production of gas, more particularly water gas, mechanical and automatic removal of the clinker formed during the operation of gas making is effected by 5 means of a grate adapted to break up the clinker masses and automatically remove the clinker and ashes from the fuel bed.

It is desirable to remove the clinker and ashes continuously or with as little interruption of gas 10 making as possible, and, in one method, the clinker and ashes are made to pass through a water seal such as for instance is provided by a water-containing ashpan in conjunction with a wall or apron depending from the generator under which the clinker and ashes are continuously 15 expelled to the outside without any interruption of gas making. In some cases, this water sealed ashpan is dispensed with and the generator entirely enclosed at the bottom, in which case 20 pockets or receptacles are formed in, and are pendant from, the casing of the generator into which pockets or receptacles the clinker and ashes are expelled and the gas making has to be interrupted in order to discharge the accumulated 25 clinker and ashes periodically, the intervals between discharges depending on the size of the pockets or receptacles.

Generally it is found inconvenient to provide 30 such pockets or receptacles of a capacity larger than sufficient to hold a few hours' supply of clinker and ashes; therefore it is necessary to interrupt gas making a corresponding number of times daily in order to discharge the ash hoppers and there is consequent loss of gas production and 35 disturbance of the uniformity of operating conditions.

The object of this invention is to enable a generator or producer of the dry or totally enclosed type to be operated with the same advantages as 40 regards continuous operation as an open or water sealed generator or producer.

For this purpose, according to the present invention, the clinker and ash receiving pocket or each such pocket of a mechanically clinkered gas 45 generator or producer of the totally enclosed type is provided with means adapted to permit the discharge of clinker and ash therefrom during the operation of the generator or producer without permitting the passage of gas or air through the pocket.

In the accompanying drawing, which illustrates diagrammatically the lower part of a mechanically clinkered gas generator or producer of the dry or totally enclosed type, one arrangement 55 of pocket with means adapted to permit discharge

of clinker and ash without passage of gas or air according to the invention is shown.

a is the wall of the generator combustible gas, *b* is a revolving grate containing a fuel bed *q* of coal, coke or the like with perforated drum *c* having perforations *c'* therein, *d* a clinker and ash discharge passage from above the grate and *e* the pocket or receptacle; there may be more than one such receptacle. The generator *a* has an air inlet *x* having a valve *x'* therein, a steam inlet *y* having a valve *y'* therein, and a gas outlet *z* having a valve *z'* therein. These serve respectively for the admission of air and steam for uprun gas making and for the outlet of downrun gas. The grate *b* is provided with a gear *r* which is driven by a worm *w* to rotate the grate.

Closures such as hinged doors *f* and *g* for closing the inlet to and the outlet from the pocket are provided and the closures are interlocked in such manner that they cannot both be open or 20 partially open at the same time but that either can be opened when the other is completely closed.

The inlet door *f* is shown hinged on pin *f'* within the pocket and the outlet door *g* is shown hinged on pin *g'* externally thereof and the hinge pins *f'* and *g'* are extended and provided with interlocking mechanism which will prevent either being turned to open unless the other be closed. In the example the hinge pins have fixed to them sector-shaped plates *f²*, *g²* and a sliding bar *h* serves by engagement with the end of one or other of the plates *f²*, *g²* to interlock the doors *f* and *g*; the bar *h* has wedge shaped ends *h¹*, *h²* which by engaging the end of the sector shaped plate of the closed door serve to force the door 30 into close contact with its seat. The sliding bar *h* is mounted in a bearing *i* and supported near its ends by abutments *j*. *k* is a lever for moving the bar *h*, and this lever may be connected by a rod *l* to any suitable form of interlocking mechanism 35 whereby the outlet door *g* is interlocked with the operating gear of the reversing valve (not shown) of the generator or producer so that the door *g* cannot be opened while gas is being made in a downward direction in the generator or producer. 40

Having now particularly described and ascertained the nature of my invention and in what manner the same is to be performed I declare that what I claim is:—

1. In a combustible gas manufacturing apparatus having a gas generating chamber adapted to contain an ignited fuel bed and having a grate in the base of said chamber, the combination of a stationary enclosed pocket for receiving clinker and ash from said chamber and for dis- 50
- 55

charging ash from said chamber and preventing the entrance of air into said chamber through said pocket, means for conveying ash and clinker from said grate to said pocket, a door controlling the flow of ash and clinker from said last mentioned means to said pocket, a second door controlling the outlet of ash and clinker from said pocket, independent means for operating each of said doors, and means independent of said operating means for said doors providing an interlock between said doors so that only one of them can be opened at one time.

2. In a self-clinkering, water gas generator having a gas generating chamber adapted to contain an ignited fuel bed and having a grate in the base of said chamber, the combination of a stationary enclosed pocket for receiving clinker and ash from said chamber and for discharging ash from said chamber and preventing the entrance of air into said chamber through said pocket, means for conveying ash and clinker from said grate to said pocket, a door controlling the flow of ash and clinker from said last mentioned means to said pocket, a second door controlling the outlet of ash and clinker from said pocket, independent means for operating each of said doors, and means independent of said operating means

for said doors providing an interlock between said doors so that only one of them can be opened at one time.

3. In a combustible gas manufacturing apparatus having a gas generating chamber adapted to contain an ignited fuel bed and having a revolving grate in the base of said gas generating chamber, the combination of a stationary enclosed pocket for receiving and discharging ash and clinker from said gas generating chamber and preventing the entrance of air through said pocket to said gas generating chamber, means for conducting clinker and ash from said grate to said pocket, a door controlling the flow of clinker and ash from said means to said pocket, a second door controlling the outlet of clinker and ash from said pocket, a sector-shaped plate connected to said first mentioned door, a sector-shaped plate connected to said second mentioned door, and a bar providing an interlock between said sector-shaped plates whereby only one of said doors can be opened at a time.

4. An apparatus according to claim 3 wherein said bar has wedge shaped ends for closing the selected one of said doors.

ARTHUR GRAHAM GLASGOW.
